John F. Collins

United States Patent Office.

JOHN F. COLLINS, OF NEW YORK, N. Y.

Letters Patent No. 91,522, dated June 22, 1869.

IMPROVEMENT IN LIQUOR-THEF.

The Schedule referred to in these Letters Patent and making part of the same.

To all whom it may concern:

Be it known that I, JOHN F. COLLINS, of the city, county, and State of New York, have invented a new and useful Sampling-Instrument, for sampling liquids and fluids of every kind; and I do hereby declare that the following is a full, clear, and exact description of the construction and operation of the same, reference being had to the accompanying drawings, making a part of this specification, in which—

Figure 1 is a sectional view of the improved sampler, ready to be used.

Figure 2 is a sectional view of one of the kinds of instruments now in use.

Figure 3 is a sectional view of the improved sampler, after the desired sample has been secured.

Figure 4 is a separate view of the inside device.

Figure 5 is a top view at the line *a b*.

The nature of my invention consists in a simple and cheap appliance for the rapid sampling of liquids or fluids, contained in any form or kind of package, without the loss usually incurred and free from the inconvenience of soiling the hands in the operation, or of being compelled to reverse the instrument in order to empty it of its contents.

The two instruments, now in general use for the purpose are as follows:

First, a plain tube of glass, tin, copper, or other suitable metal, constructed substantially in the form shown in fig. 1, without the inside device, in which—

A is the tube;

B, the handle;

C, the tapered end; and

D, the cap.

It is operated by submerging as much of the lower part of the instrument as may be desired in the liquid contained in the barrel, cask, or other package.

As the liquid rises in the tube, the air is correspondingly displaced, and the operator, having filled the tube as far as desired or possible, places his thumb over the small hole in the cap D, suddenly withdraws the instrument, and stops the lower opening with the finger of the other hand, thus retaining the sample in the tube.

If, however, the quantity in the package be too small to allow the fluid to rise in the tube far enough to furnish the required sample, the air is exhausted by placing the mouth over the hole in the cap D, and drawing or sucking the liquid up into the tube.

Second, an instrument of somewhat similar construction, with the tapered end at the top, the tube cut square off at the bottom, and a small ball-valve closing the opening of an inner cone, as shown in fig. 2.

This instrument is operated by moving it up and down rapidly in the liquid until the required quantity

has been pumped into the tube. It is then withdrawn, and emptied by turning it upside down.

The object of this invention is to overcome the inconveniences and loss attending the use of either of the above-mentioned instruments, and also to perform the operation with the use of one hand only.

This is accomplished by introducing into the tube the appliance shown in fig. 4, in which—

E is a ring;

G, a tapered stopper or plug, of cork, rubber, or other suitable substance, having an opening vertically through its centre;

H, a valve, to open and close the same; and

F, a rod of wire, or small tube, connecting the ring and stopper, and in such a manner as to form guards over the valve H.

Having described the nature of my invention, I will now describe its operation.

The operator takes the instrument by the handle B, and, passing the end of the thumb or finger into the ring E, slightly raises the rod F and stopper G, as shown in fig. 1. The lower part of the instrument is then submerged in the fluid to the desired depth, when the ring E is pressed downward, thus, by means of the rod F pressing the tapered stopper or plug into the tapered end of the instrument C, effectually closing it, and retaining the whole sample, subject to the will of the operator, without fear of loss, and leaving the other hand free.

If, however, the depth of the liquid in the package should not be great enough to admit as large a sample into the tube as is desired, the instrument is held open, as shown in fig. 1, a moment, when first introduced. It is then closed by forcing the plug G to its seat, as already described, and then moved rapidly up and down in the liquid, securing the same result as in the use of the instrument shown in fig. 2. Having secured the sample, the instrument is emptied by simply raising the plug G, instead of being compelled to reverse it.

Having described my invention,

What I claim as new, and desire to secure by Letters Patent, is—

An instrument for sampling fluids, consisting of the tube A, ring E, rod F, perforated plug G, valve H, combined, constructed, and operated substantially as described and set forth.

In testimony whereof, I have hereunto set my signature, this 22d day of February, A. D. 1869.

JOHN F. COLLINS.
